UNITED STATES PATENT OFFICE.

ORLANDO F. SMITH AND GEORGE H. BARBOUR, OF WASHINGTON, DISTRICT OF COLUMBIA.

SEAL FOR DIP-PIPES.

SPECIFICATION forming part of Letters Patent No. 397,032, dated January 29, 1889.

Application filed September 4, 1888. Serial No. 284,571. (No model.)

To all whom it may concern:

Be it known that we, ORLANDO F. SMITH and GEORGE H. BARBOUR, citizens of the United States, residing at Washington, in the 5 District of Columbia, have invented new and useful Improvements in Seals for Dip-Pipes, of which the following is a specification.

Our invention relates to that class of devices denominated "seals for dip-pipes."

- 10 In the manufacture of illuminating-gas prior to our invention the rising pipe has usually been carried from the retort to a point above the hydraulic main, and thence curved downward to enter said main, its open foot 15 dipping in the water therein. The gas-valve, seating in an opening in the foot, is mounted on a valve-stem which passes up through an opening in the main and through a short pipe tapped into said opening, and upon its ex- 20 posed end it carries an inverted cup, which dips into an annular water-chamber formed by surrounding the short pipe rising from the main by a cylindrical vessel, ample space being allowed for the dip of the inverted cup.
- 25 The valve-stem is coupled to a lever, by which it is operated in any suitable manner to raise the gas-valve and permit the gas to pass into the hydraulic main, or to seat said valve and check the flow of gas from the retort.
- 30 The difficulty hitherto experienced with appliances of this class has been that the accumulation of tar in the annular chamber of the external water seal soon interfered with the descent of the inverted cup carried by the 35 valve-stem and prevented the proper seating of the gas-valve. So rapid is this accumulation that it has sometimes been found necessary to dismantle the apparatus and dig out the hardened tar with an instrument as often 40 as once in twenty-four hours. As each retort in a gas-manufactory is provided with a similar appliance, the time and labor involved in cleansing the same has been a serious item of expense, besides the loss of the tar removed, 45 which in large gas-works is considerable.

It is the purpose of our invention to provide a simple valve mechanism which may be substituted for the external water seal, and which is so organized that the deposited tar 50 shall flow directly back into the hydraulic

main, instead of accumulating upon or within any part of the apparatus.

It is also our purpose to dispense with the external water seal and to provide an extremely simple duplex valve, whereby the 55 same results shall be perfectly accomplished, the necessity of frequent cleansings being wholly avoided and the loss or waste of tar prevented.

The invention consists in the several novel 60 features of construction and new combinations of parts hereinafter fully described, and then specifically pointed out in the claims.

In the accompanying drawings, Figure 1 is a side elevation showing our invention applied, the hydraulic main and dip-pipe being shown in dotted lines. Fig. 2 is a central vertical section showing the parts which constitute our invention.

In the said drawings, the reference-numeral 70 1 designates the hydraulic main, and the numeral 2 denotes the rising pipe or dip-pipe, curved over the main and descending therein through its upper wall, its foot 3 dipping in the water lying in the main in the usual manner. All these parts, being of the ordinary 75 and well-known construction, require no specific description in this specification.

The foot 3 of the dip-pipe is provided with the usual gas-opening in its upper wall, and 80 in this opening is formed a seat to receive the gas-valve 4. This valve is by our invention mounted upon a rigid valve-stem, 5, which passes through an opening in the upper wall of the hydraulic main. Into this opening is 85 tapped a short pipe, 6, having an interior diameter which is somewhat in excess of the diameter of the valve-stem 5. Upon the upper end of the short pipe is mounted a cup, 7, and within said cup or near to the mouth 90 of the pipe 6 is formed a valve-seat, 8.

Upon a threaded flange, 9, of the cup 7 is screwed a similar inverted cup, 10, having a central opening, 12, of such dimensions as to permit the free passage of the valve-stem 5, 95 which extends above it, and provided with a valve-seat, 13, surrounding said opening.

Upon the upper portion of the valve-stem, which lies within the chamber formed by the two cups 7 and 10, and which is threaded for 100

the purpose, is mounted a duplex valve, 14, having a female thread which engages the thread on the stem. Valve-faces 15 upon this valve are so cut that when the stem is raised the valve will close the opening 12 in the inverted cup, while by lowering the valve-stem the duplex valve will rest upon the seat 8 and close the mouth of the short pipe 6.

The end of the valve-stem which rises above the opening 12 of the cup 10 is pivotally coupled to an actuating-lever, 16, arranged in any suitable manner to be operated by a rod connected to the power end of said lever and brought within reach of the operator.

In adjusting the parts the duplex valve 14 is so arranged upon the threaded part of the stem 5 that when the gas-valve 4 is seated in the foot of the dip-pipe the duplex valve will also rest upon its seat 8 and close the mouth of the pipe 5.

The interior wall of the chamber formed by the union of the two cups 7 and 10 is so shaped that the tar deposited therein flows easily and naturally through the pipe 6 into the hydraulic main, the heat of the parts rendering the tar sufficiently fluid to insure its immediate return, thereby preventing all danger of accumulation and avoiding the necessity of removing and cleaning the parts. Should this be deemed necessary at any time, the valve-stem is disconnected from the lever and the cup 10 is unscrewed, after which the cleansing of the interior of both cups may be readily and quickly effected. Under ordinary circumstances, however, this will seldom if ever be essential. When the operator lifts the valve-stem and unseats the gas-valve 4 to permit the gas to flow from the retort into the main, the duplex valve 14 instantly seats upon the valve-seat 13, closing the exit from the chamber and preventing loss of gas from the main.

What we claim is—

1. The combination, with a hydraulic main and with a dip-pipe entering said main, of a gas-valve seating in an opening in the foot of the dip-pipe, said valve being carried by a valve-stem which rises through a short pipe of greater diameter tapped into said main, and provided with a chamber at its end containing two valve-seats, one surrounding the mouth of the short pipe and the other surrounding an opening in the top of said chamber, the valve-stem extending through the latter opening and provided with an adjustable duplex valve arranged within the chamber to seat and close the short pipe at the same time the gas-valve seats in the foot of the dip-pipe, and to seat around and close the opening in the

top of the chamber when the gas-valve is opened, substantially as described.

2. The combination, with a hydraulic main having a short pipe tapped through its walls, of a dip-pipe entering said main, a valve-stem passing loosely through the short pipe and carrying on its end a gas-valve seating in an opening in the foot of the dip-pipe, a duplex valve having two separate valve-faces lying in a chamber formed on the end of the short pipe and provided with a valve-seat surrounding the mouth of said pipe, and a separate seat surrounding an opening in the top of said chamber, through which the valve-stem loosely passes, said duplex valve having a female thread, by which it is adjustable upon a threaded portion of the stem, substantially as described.

3. The combination, with a hydraulic main having a short pipe tapped through its wall and provided upon its end with two separate cups forming a chamber, of a dip-pipe entering the main, a valve-stem passing loosely through the short pipe and its chamber, and having a gas-valve at its end seating upon an opening in the foot of the dip-pipe, a duplex valve adjustably mounted on the valve-stem within the chamber at the end of the short pipe, said duplex valve seating alternately around the mouth of said pipe and around an opening in the top of the chamber, through which the valve-stem loosely passes, and means for raising and lowering said valve-stem, substantially as described.

4. The combination of a hydraulic main, a dip-pipe curved over the main, descending thereinto, and having a foot dipping in the liquid, and provided in its top wall with a gas-valve seat, a pipe secured to the main, rising therefrom, and provided at its top with a sectional cup containing an upper and a lower valve-seat, a rigid valve-stem extending up through the cup-carrying pipe and through the cup thereon, having a valve at its lower end to close on the valve-seat of the foot on the dip-pipe, and provided with a duplex-faced valve located in the cup and adapted to close alternately upon the upper and lower valve-seats thereof, and a lever suitably connected with the valve-stem above the cup for operating said stem and its valves, substantially as described.

In testimony whereof we affix our signatures in presence of two witnesses.
